GAS-CONVERSION APPARATUS

Frederick P. Wilson, Jr., Schenectady, N. Y., assignor to General Electric Company, a corporation of New York

Application March 6, 1930, Serial No. 433,725

3 Claims. (Cl. 48—65)

The present invention relates to the manufacture of combustible gas having a high hydrogen content and either a predetermined low content of hydrocarbon gas or being substantially free from hydrocarbon gas as desired.

It is the object of my invention to produce a gas mixture suitable for such industrial operations as the brazing and annealing of metals, electric welding involving dissociated or atomic hydrogen, the cutting of metals by a flame, the reduction of metals from their oxides and other purposes requiring a gas having reducing properties.

My invention comprises an apparatus for treating a hydrocarbon gas, or a gaseous mixture containing a hydrocarbon gas, at an elevated temperature which is chosen and maintained to cause to be derived from such hydrocarbon a gaseous product of predetermined composition, such gas either being substantially non-carburizing or having a controllable carburizing or decarburizing property.

My new gas generator is adapted to provide in steady, regulated volume a non-carburizing reducing gas, such as hydrogen or carbon monoxide, or both, which is either substantially unassociated with hydrocarbon gas or contains a predetermined, definite proportion of a stable, normally gaseous hydrocarbon, such as methane with or without inactive gases such as nitrogen.

A typical gaseous product made by the practice of my invention comprises about 75 per cent of hydrogen, about 20 per cent carbon monoxide, and about 1 per cent of methane, the remainder being inactive constituents, such as nitrogen.

The novel features of my invention are set forth with greater particularity in the accompanying claims. For a complete understanding of my invention reference may be had to the following description taken together with the accompanying drawing in which Fig. 1 is a somewhat conventionalized side elevation illustrating the relation of mixing device, gas reaction chamber, and steam control device; Fig. 2 is a vertical section of a reaction chamber for subjecting gaseous mixtures to a predetermined high temperature; and Fig. 3 is a side elevation illustrating a modified gas feed apparatus.

Referring to the drawing, a carbon-containing gas, such as a fuel gas of the character employed for city gas supply, which commonly comprises a substantial proportion of normally gaseous hydrocarbons, is introduced by a supply pipe 3 to a mixing device 4. Such a fuel gas usually comprises hydrogen, carbon monoxide, methane and

higher hydrocarbons of the methane series commonly known as "illuminants". As examples of such gas, coal gas, natural gas, coke oven gas and producer gas may be mentioned. A hydrocarbon gas such as butane may be employed. Steam may be admitted to the mixing device by a supply pipe 5, the steam flowing through a valve 6, which is controlled by a temperature-responsive device 7, whereby the amount of steam admixed with the hydrocarbon gas is controlled. The device 7 operates to vary the steam supply in response to the temperature of the gas-steam mixture in the chamber 4 so as to maintain a constant ratio of gas and steam in the reaction mixture delivered to the reaction chamber 8 by the pipe 9, emerging from the mixing device. I may use for elements 6 and 7, a steam controller such as sold in the open market for controlling steam flow in response to temperature variations. Thermostatic or pyrometer operated electric apparatus for varying the steam supply likewise may be used. Such devices are known in the art and hence will not be here described. The steam controller comprises a steam valve operated by a mechanism which is responsive to the temperature of a medium (in this case the mixture in 4) through the intermediary of a gas, or other fluid, under pressure. The temperature of the gaseous mixture in the chamber 4 may be observed from a thermometer 11. Its temperature will vary with the rate of steam flow.

With a proper setting of the control device, the ratio of gas and steam is maintained constant regardless of variations of gas or steam pressure. Should the ratio of steam tend to fall, then the temperature of the mixture in the chamber 4 will fall and the device 7 will open the steam valve causing more steam to be admitted. Conversely a rise in steam ratio will result in an increased liberation of heat in the mixing chamber and cause the device 7 to reduce the flow of steam by reducing the aperture of the steam valve. As already stated above, the steam admixture may be omitted. In that event dissociated carbon accumulates in the reaction chamber and should be removed from time to time.

The gas, or gas and steam, mixture passes from the pipe 9 through a heat interchanger 10 to the reaction chamber 8 where it is subjected to a temperature within the range of about 700 to 1100° C., causing dissociation and if steam is present causing the dissociated carbon to react with the water vapor to form hydrogen and carbon monoxide. Ordinarily a temperature of about 1000° C. is employed. At this temperature

a small amount of methane (about 1%) remains in the reaction product. For many industrial operations this amount of hydrocarbon residue either is not harmful, or is desirable and beneficial, particularly for carrying out brazing operations such as described in United States Patent 1,528,581, issued March 3, 1925, to Christian Steenstrup. If a greater amount of hydrocarbon gas is desired as for carburizing metals, a lower 10 temperature is employed in the reaction chamber.

At a temperature of about 1100° C., the decomposition of the hydrocarbon gas is so nearly complete into hydrogen and carbon that the remaining hydrocarbon is negligible. Even higher temperatures may be employed if desired to entirely 15 eliminate the hydrocarbon. If water vapor is present in proper proportion the carbon is completely converted to carbon monoxide at 1000° C.

As illustrated in Fig. 2, the reaction chamber 20 comprises a metal shell 12 within which is located a firebrick wall 13, resting on a base 14. Mounted on the wall 13 is a distributing chamber 15 which communicates by a conduit 16 with the heat interchanger 10 and in fact constitutes part 25 of the heat interchanger. The shell 12 is lined with a finely divided heat insulator 17, such as finely divided silica. An electric resistor 18 is supported by hangers 19 of refractory material, which are built into the wall 13 and project therefrom. This resistor preferably comprises a pleated ribbon of nickel-chromium alloy which has an incidental catalyzing effect upon the gaseous reaction or gasifying occurring in the reaction chamber but principally functions to radiate 30 sufficient heat to produce a desired high temperature in the reaction mixture. Suitable external electric regulating devices (not shown) may be used to control the temperature of the electric heater.

40 The gas mixture entering the chamber 15 passes through the iron tubes 20, in which it becomes heated, to a region near the bottom of the converter and passes upward in a counter current path in contact with the resistance heater 45 and adjacent heated parts whereby chemical equilibrium is established and a product of desired definite and maintained composition is formed. The gaseous product emerges from the reaction zone by the conduit 21 and may be supplied to a brazing furnace or other industrial device. In a brazing furnace a content of carbon monoxide is desirable to prevent oxidation of ferrous metal during cooling. A content of 55 hydrocarbon gas in the neighborhood of one per cent is desirable to combine with water vapor which is unavoidably present in a brazing furnace.

The gaseous product, which is constituted mainly of hydrogen, and carbon monoxide, together, with an exactly predetermined proportion of hydrocarbon gas, is suitable for many metallurgical operations in which the carbon content of the metal should be accurately controlled. For such operations a furnace or oven 60 atmosphere can be maintained neutral, decarbonizing or carburizing by the practice of my invention. In a copending application Serial No. 433,726, filed March 6, 1930, I have described and 65 claimed metallurgical apparatus and processes employing such gaseous products as an enveloping atmosphere.

70 Some nitrogen, say about 4 or 5 per cent, is usually present in the fuel gas commonly furnished by city gas companies. For some metal-

urgical operations a larger proportion of diluent is desirable. For some purposes a nitrogen content as high as 95 per cent is employed, the rest of the mixture consisting of hydrocarbon or carbon monoxide. Such a mixture is non-inflammable and when dry is reducing chemically. 80

If it is desired to produce a gaseous mixture for metallurgical operations having a substantial content of inactive gas, such as nitrogen, and carbon dioxide, some of the fuel gas fed to the converter is first burned by mixing with such amount of air that incomplete combustion is produced. In that event a modified gas feeding system is employed as is illustrated in Fig. 3. In this figure a combustion chamber 23 is inserted into the gas supply line 3 by closing the valve 24 and opening the valve 25 in a supply pipe 26 of the combustion chamber, which is also supplied with air or other combustible gas under pressure through a pipe 27. A flame is produced at the orifice of the air supply pipe 27 which burns in the surrounding atmosphere of fuel gas in the combustion chamber 23 and consumes part of the fuel gas forming carbon dioxide, carbon monoxide, and water vapor. These products, together with the nitrogen 100 introduced as part of the air, are carried through the pipe 28 into the mixing chamber 4. It is desirable in some cases to remove the water vapor from the gaseous mixture in pipe 28. This can be done in any convenient way, as for example by passing the gases through a condenser 29 and drawing off the condensed water. In some cases the water vapor may be retained in the gaseous mixture and a correspondingly lesser quantity of steam admitted to the mixing 110 chamber, so as not to disturb the gas and steam ratio. The hydrocarbon gas in some cases may be wholly decomposed and oxidized in the combustion chamber 23, the reaction chamber 4 then being unnecessary. 115

What I claim as new and desire to secure by Letters Patent of the United States, is:

1. A gas generator comprising the combination of means for mixing unlike gases in predetermined proportions, a distributing chamber 120 communicating with said mixing means, a reaction chamber, conduit means communicating at one end with said distributing chamber, being open at the opposite end to said reaction chamber, and projecting into said reaction chamber, a radiant heater located in said reaction chamber, said heater being constructed to produce the high temperature at which a gaseous mixture passing through and emanating from said conduit means will chemically react, and an outlet conduit for 125 said reaction chamber.

2. A gas generator comprising the combination of a device for mixing unlike gases capable of chemical reaction, means for maintaining said gases in predetermined ratio at different feed 135 pressures, a distributing chamber communicating with said device, a reaction chamber, a common heat-insulating enclosure enveloping said distributing and reaction chambers, a plurality of tubes each communicating at one end with said distributing chamber, extending through a substantial part of said reaction chamber and at the opposite end having orifices communicating with said reaction chamber, a radiant heater in said reaction chamber, and an outlet conduit for 140 said reaction chamber.

3. An apparatus for generating combustible gas comprising a mixing device, means for maintaining the delivery of unlike gases to said mixing device constant at different pressures, a distribut- 150

ing chamber, an input conduit connecting said device and said chamber, a gasifying chamber, a radiant heater of nickel-chromium alloy in said gasifying chamber, a plurality of tubes each communicating at one end with said distributing chamber and extending throughout substantial-
5 ly the length of said gasifying chamber, and hav-

ing at their opposite ends discharge orifices com-
municating with said gasifying chamber, and an
outlet conduit communicating with said gasify-
ing chamber in heat-interchanging relation to
said input conduit.
